UNITED STATES PATENT OFFICE.

JAMES A. SKAER, OF AUGUSTA, KANSAS.

DESIGN FOR A PENCIL-HOLDER.

SPECIFICATION forming part of Design No. 33,325, dated October 9, 1900.

Application filed September 11, 1900. Serial No. 29,731. Term of patent 7 years.

To all whom it may concern:

Be it known that I, JAMES A. SKAER, a citizen of the United States, residing at Augusta, in the county of Butler and State of Kansas, have invented and produced a certain new and original Design for Pencil-Holders; and I do declare the following to be a full, clear, and exact description of the invention, such as will enable others skilled in the art to which it appertains to make and use the same.

The invention relates to a new and original design for a pencil-holder; and it consists of the design of the shape and configuration shown in the accompanying drawings, in which—

Figure 1 is a front view of the pencil-holder. Fig. 2 is a side elevation, and Fig. 3 is a top plan view.

The leading features of the design comprise a vertically-disposed loop 1, extending out-

wardly at its lower end and having the material constituting the loop extending forwardly at its upper end in the shape of a twist 2, which terminates in two oppositely-directed superposed coincident coils 3 and 4, 25 offset to the inner side of the vertically-disposed loop.

Having thus fully described my invention, what I claim, and desire to secure by Letters Patent, is—

The design for a pencil-holder, as herein shown and described.

In testimony whereof I have hereunto set my hand in presence of two subscribing witnesses.

JAMES A. SKAER.

Witnesses:
